L. S. MILLER, G. SENSABAUGH AND W. D. SHELBY.
POLE RAISING AND STRAIGHTENING DEVICE.
APPLICATION FILED JULY 2, 1920.

1,403,337.

Patented Jan. 10, 1922.

UNITED STATES PATENT OFFICE.

LEONARD S. MILLER, OF CINCINNATI, GEORGE SENSABAUGH, OF DAYTON, AND
WILLIAM D. SHELBY, OF COLUMBUS, OHIO.

POLE RAISING AND STRAIGHTENING DEVICE.

1,403,337.

Specification of Letters Patent. Patented Jan. 10, 1922.

Application filed July 2, 1920. Serial No. 393,691.

To all whom it may concern:

Be it known that we, LEONARD S. MILLER, GEORGE SENSABAUGH, and WILLIAM D. SHELBY, citizens of the United States of 5 America, and residents of Cincinnati, Dayton, and Columbus, respectively, in the counties of Hamilton, Montgomery, and Franklin, respectively, and State of Ohio, have invented a new and useful Improvement 10 in Pole Raising and Straightening Devices, of which the following is a specification.

An object of our invention is to provide a device that may be used to raise and 15 straighten telephone poles, telegraph poles, and poles used for other and similar purposes.

Another object is to decrease the load upon the men who raise such poles, and to reduce

A. The shoulders b^2 formed on the plate B 55 adjoin the lug b and limit the extent to which the collar d^2 on the support D projects over the lug b .

The pole support D is circular and has a series of teeth d upon its inner surface, said 60 teeth being adapted to grip a pole F. A shank d' is formed on the support, and has attached to it the collar d^2 by means of the bolt a^3 extending through such collar and shank. The collar d^2 is adapted to be 65 mounted upon the lug b on the plate B, whereby the support D may be held in alignment with the jack bar A.

A series of links E comprising hollow metallic tubes e having a bore e' substantially equal to the bore d^4 of the collar d^2 . 70 A pin e^2 is mounted in the bore e' and extends from one end of the link E. The pin e^2 extends through the shoulder b^2 of the plate B and through the shoulder b^3 of the plate C.

- plate, a lug upon the plate, means to secure the plate to the jack bar, and a pole support adapted to be mounted upon the lug. 2. The combination with a jack bar, of a plate, a lug upon the plate, means to secure the plate to the jack bar, a pole support, a shank on the support, and a collar upon the shank adapted to engage the lug on the plate. 10 3. The combination with a jack bar, of a plate, bolts securing the plate to the jack bar, a lug on the plate extending beyond and in alignment with the jack bar, a pole support, and a collar on the support adapted to engage the lug on the plate and to secure the support in alignment with the jack bar. 15 4. The combination with a jack bar, of a plate, a lug upon the plate, means to secure
- the plate to the jack bar, a pole support adapted to be mounted upon the lug, and a series of links adapted to be interposed between the lug and the pole support. 5. The combination with a jack, of a lug mounted on the jack, and a pole support adapted to be mounted on the lug. 25 6. The combination with a jack, of a lug mounted on the jack, a pole support adapted to be mounted on the lug, and links adapted to be interposed between the lug and the pole support. 30

In witness whereof, we have hereunto subscribed our names this 29th day of June, 1920.

LEONARD S. MILLER.
GEORGE SENSABAUGH.
WILLIAM D. SHELBY.
